SHEET MATERIAL ELEMENT USED IN
FEEDING DEVICE

Ernst C. Sauerman, Chicago, Ill.

Original application June 5, 1948, Serial No. 31,338. Divided and this application September 16, 1950, Serial No. 191,071

3 Claims. (Cl. 101—149.4)

1

This invention relates to improvements in a folded sheet or card which can be employed as a printing card and is a division of my copending application Serial No. 31,338, filed June 5, 1948.

One of the objects of my copending application, hereinbefore identified, resides in the provision of means for periodically removing the lowermost folded sheet from a stack of such sheets and conveying the removed sheet forwardly to an operating station.

Another important object of the invention described in my said copending application resides in the provision of means for conveying the folded sheets aforesaid from the stack of sheets to the operating station at a predetermined linear speed, and feeding said sheets in the operating station between opposed rolls whose peripheral speed is different from the speed of feeding whereby said sheets pass between said rolls in overlapping relationship.

An important feature of the invention described in my said copending application comprises means for overlapping the sheets between the rolls which can be conveniently changed to change the degree of overlap of the sheets between the rolls.

Another important feature of the invention described in my said copending application resides in means which positively conveys the sheets forwardly to the operating station at a predetermined speed and which disengages from said sheets at the moment or slightly prior thereto that the sheet is brought under the control of the slower moving conveying elements at said station, whereby injury to the sheet is prevented at the period of transition of traveling speeds of the sheet.

An important object of the present invention resides in the provision of a folded sheet or card which can be employed as a printing card, said card being readily engageable by the conveying means hereinbefore mentioned and from which the conveying means can be readily and quickly disengaged, the card carrying transferable indicia which is protected during use of the card in the machine from smearing adjacent cards during removal of the card from the stack; the card is also constructed that the indicia carried thereon is so positioned as to permit a maximum degree of overlapping at the printing station.

Other objects and advantages of the present invention will be apparent from the accompanying drawings and following detailed description.

Fig. 1 is a longitudinal view, parts being shown in section, of a machine with which my card may be used.

2

Fig. 2 is a detailed plan view of the conveyor employed in the machine shown in Fig. 1, illustrating the function and operation of the conveyor fingers.

5 Fig. 3 is a face view of the bottom card of an inverted stack of printing cards usable with the present machine.

Fig. 4 is an end view of the card shown in Fig. 3.

10 Fig. 5 is a view of the reverse face of the card illustrated in Fig. 3.

Fig. 6 is a sectional view of an inverted stack of cards, taken on line 6—6 of Fig. 3.

15 Referring particularly to the drawings, 1 indicates the base of a machine upon which my card may be used, a pair of side frame members 2 being mounted upon said base in vertical position and in spaced parallel relationship. The side frame members 2 are maintained in spaced 20 relationship by means of transverse bar 3, only one of which is shown in Fig. 1.

25 A shaft 4 is journalled at its opposite ends in the opposite frame members 2 and a second shaft 5 is similarly journalled at the opposite end of the machine. A pair of sprocket wheels 6, only one of which is shown, are carried upon the shaft 4 and are disposed adjacent the inner faces of the side members 2. Similarly a pair of sprocket wheels 7, only one of which is shown, are carried upon shaft 5 adjacent the inner faces of the side members 2 and in alignment with the respective sprocket wheels 6 upon shaft 4. A suitable prime mover (not shown) may be connected to shaft 4 whereby the machine may be driven.

30 35 A sprocket chain 8 is trained around one pair of sprocket wheels 5 and 6 and a sprocket chain 9 is similarly trained around the remaining pair of sprocket wheels 5 and 6, the path of travel of the sprocket chains at their upper passes being adjacent the upper edges of the frame members 2.

40 45 A pair of upwardly extending standards 10 are secured to the opposite frame members 2 adjacent one end of the machine. This end of the machine will hereinafter be referred to as the delivery end. A shaft 11 is journalled at its ends in suitable bearings carried by the opposite standards 10, and one end of said shaft extends outwardly from one of the standards and is suitably driven in timed relationship to shaft 4. A rubber covered roll 12 is mounted upon an intermediate portion of shaft 11 for purposes which will be hereinafter more fully described.

50 55 A steel or other hard surfaced roll 13 is positioned beneath roll 12 in slightly offset vertical relationship with said latter roll. Roll 13 is car-

ried upon a shaft 14, the opposite ends of which are journalled in the ends of a pair of bell crank levers 15, only one of which is shown in Fig. 1. The bell crank levers 15 are journalled intermediate their lengths upon stub shafts 16 carried by one of the frame members 2. Coil springs 17 are connected respectively at their ends to the ends of the bell crank levers 15, and both of said springs are anchored upon rod 6' at their opposite ends, as shown best in Fig. 1.

The arrangement is such that roll 13 is urged upwardly into pressure contact with roll 12 by means of the tension in springs 17, said springs tending to rock levers 15 upon their respective shafts 16.

Broadly, the primary function of the machine is to feed sheet material comprising the present invention forwardly from a supply station to an operating station. The character of the sheet material which is fed forwardly may vary, as for instance, it may comprise printing units, that is, elements which may be used to transfer indicia carried by said units to another sheet or web. The sheet material units are fed forwardly to the operating station which may comprise simple pressure rolls between which the units transfer their indicia to a sheet or web which may be passed between the rolls in company with the units.

From the physical point of view, apart from specific function, the units fed forwardly are relatively flat so that they can be conveniently stacked and may comprise cardboard, paper, celluloid or like plastic sheet material, thin metal or the like, and they are so constructed as to provide a channel, a fold in the case of a cardboard card or the like, whereby conveying members may engage to carry the same forwardly. From a physical aspect the operating station, apart from its function, preferably comprises rotating members which act to carry the unit delivered thereto forwardly in addition to performing a specific function such as pressing, printing or the like.

For purposes of illustrating the use of my invention, the unit employed comprises a printing card. Reference is specifically made to Figs. 3, 4, 5, and 6. In the drawings a card 18 is illustrated as comprising a flat sheet of relatively thin cardboard which is folded intermediate its length to form a flap 19 and is folded adjacent the opposite end to form a sub-panel 20. The panel 20 is adhesively secured to the main panel 21, said portion of the card being provided with an elongated aperture 22, one side of which is defined by the fold 23 which joins the flap to the main panel 21. The inner face of the flap comprises a portion 24 which appears through the aperture 22. Upon that portion 24 of the flap which is visible through aperture 22, indicia 25 is carried, the indicia comprising information which may be inscribed upon the portion 24 by an ink which can be rendered transferable when moistened with a predetermined liquid.

A plurality of cards 18 are adapted to be stacked, as shown best at 26 in Fig. 1 in a hopper 27. The hopper 27 may comprise frame members 28 which define a space so dimensioned as to accommodate the cards 18.

Adjacent the rear end of the hopper, the frame members are bent inwardly and upwardly as shown best at 29 in Fig. 1 whereby the lowermost card 18 of the stack 26 is carried adjacent the edge of the card 18 which carries sub-panel 20.

It can readily be seen that when the stack 26 of cards 18 is positioned in the hopper, the stack 75

being arranged with the flaps 19 of the cards disposed downwardly, the lowermost card is supported along one edge by the inturned flanges 29 and the opposite edge of the card is supported by ends 30 of cross members 31. However, as the cards approach the lowermost position, the lowermost card slides laterally in offset relationship to the stack 26 as shown best at 32 in Fig. 1 whereby the flap 19 drops by gravity so as to dispose the flap at an acute angle to the main panel 21 of the lowermost card 18. The position of the hopper 27 with respect to the chains 8 and 9 is such that the flap 19 drops to a position between the upper passes of said chains.

10 A plurality of blocks 33 are positioned upon each chain 8 and 9, the blocks on each chain being spaced from each other and the blocks on opposite chains being in alignment with each other. Each block 33 carries a bell-crank lever having a finger 34 and an arm 35, the bell-crank lever in each case being pivotally secured to a block by means of screw 36.

As the chains move and a pair of blocks 33 pass beneath the hopper 27, the fingers 34 carried by the opposite blocks engage in the fold of the lowermost card 18, that is, the fold made by the connection of the flap 19 and main panel 21 of the card. It will be noted that the lowermost card, in shifting laterally with respect to stack 26, causes the flap of said card to swing downwardly, opening up the fold to a predetermined degree and thereby permitting the ready entrance of the fingers 34 into engagement with said fold. As the chains move forwardly, the lowermost card 18 is thus extracted from the stack 26 and is carried forwardly by the engagement of the fingers 34 in the fold of the card.

30 In view of the fact that the lowermost card 18 is removed from the stack 26 in a sliding fashion, there would be a tendency for the typed material 25 upon the lowermost card to smudge the rear face of the flap 19 of the card immediately above during the sliding motion. This tendency is completely avoided by the fact that the depth of the typed material 25, that is, its thickness upon the surface of the flap 19 is less than the thickness of the card proper and, hence, the main panel 21 of the card protects the typed matter 25 from coming into contact with the rear face of the flap of the card immediately above.

40 In addition, as can readily be seen by reference to Fig. 1, by virtue of the manner in which cards are supported in the hopper, the flap 19 of the lowermost card drops downwardly and, consequently, that portion of the flap which carries the typed matter 25 is removed from the rear face of the flap of the card immediately above. Consequently, although the ink or other matter employed to form the type 25 may be of appreciable thickness, and may readily be removed by contact or abrasion, it is protected from such removal both by the structure of the hopper and by the structure of the card itself.

50 The cards 18 removed from the hopper are carried toward rolls 12 and 13 and are disposed in overlapping relationship between said rolls. The desired overlap of the cards in the nip of the rolls 12 and 13 is such that the fold of one card within the nip, that is, the fold between the main body of the card 21 and the flap 19, is disposed along the opposite longitudinal edge of the aperture 24 from that edge which comprises a continuation of the fold of the card immediately beneath. Preferably the width of the cards is such that three or four cards will be

disposed in overlapping relationship between the rolls 12 and 13. However, the number of cards disposed in overlapping relationship in the nip is a factor which can easily be determined by any one skilled in the art to adopt the machine to a predetermined operation.

It is desirable in transferring the impression of indicia 25 upon web 37 that the individual indicia of adjacent units 18 be spaced, in transfer, as closely as possible upon web 37. Hence, the desirability of overlapping the units in the operating station and also the desirability of positioning the aperture 24 in each card as close as possible to the leading edge of the card.

Another feature of the card construction which is of importance is that the flap 19 is shorter in width than the main panel 21 of the card and that the sub-panel 20, when the card is in collapsed position, as shown best in Fig. 4, is disposed with its edge closely adjacent the free edge of the flap 19. By this arrangement the cards are of substantially uniform thickness throughout and, hence, when stacked, as in the hopper 27, the individual cards will occupy a substantially horizontal position throughout the height of the stack and will not be canted at a cumulatively changing angle from the bottom of the stack to the top thereof.

I claim as my invention:

1. A printing unit from which an impression of indicia carried thereby is transferable by pressure contact to a print receiving surface which comprises, sheet material folded intermediate one of its dimensions to form a main panel and a flap, an edge of the main panel extending outwardly beyond an edge of said flap to permit the flap to swing downwardly from the main panel when the panel is substantially horizontally positioned, indicia formed of transferable material carried upon the surface of the flap adjacent said fold, the main panel being provided with an aperture adjacent said fold with the defining edges of said aperture bordering said indicia whereby the indicia is exposed through said aperture, the faces of said indicia extending from the surface of said flap a distance less than the thickness of the main panel whereby units disposed in face-to-face relationship can slide upon each other without smudging the indicia carried on the flap of one of the face-to-face adjacent cards.

2. A printing unit from which an impression of indicia carried thereby is transferable by pressure contact to a print receiving surface which comprises, sheet material folded intermediate one of its dimensions to form a main panel and a flap, an edge of the main panel extending outwardly beyond an edge of said flap to permit the flap to swing downwardly from the main panel when the panel is substantially

horizontally positioned, indicia formed of transferable material carried upon the surface of the flap adjacent said fold, the main panel being provided with an aperture defined at one edge by a continuation of said line of fold with the defining edges of said aperture bordering said indicia whereby the indicia is exposed through said aperture, the faces of said indicia extending from the surface of said flap a distance less than the thickness of the main panel whereby units disposed in face-to-face relationship can slide upon each other without smudging the indicia carried on the flap of one of the face-to-face adjacent cards.

3. A printing unit from which an impression of indicia carried thereby is transferable by pressure contact to a print receiving surface which comprises, sheet material folded intermediate one of its dimensions to form a main panel and a flap, an edge of the main panel extending outwardly beyond an edge of said flap to permit the flap to swing downwardly from the main panel when the panel is substantially horizontally positioned, indicia formed of transferable material carried upon the surface of the flap adjacent said fold, the main panel being provided with an aperture adjacent said fold with the defining edges of said aperture bordering said indicia whereby the indicia is exposed through said aperture, the faces of said indicia extending from the surface of said flap a distance less than the thickness of the main panel whereby units disposed in face-to-face relationship can slide upon each other without smudging the indicia carried on the flap of one of the face-to-face adjacent cards, a sub-panel of a thickness substantially equal to that of said flap, said sub-panel being carried by said main panel and disposed in substantially face-to-face relationship with the main panel with an edge of the sub-panel disposed adjacent the face edge of the flap.

ERNST C. SAUERMAN.
